UNITED STATES PATENT OFFICE.

MILLARD F. ROEBLING, OF CINCINNATI, OHIO.

TIME-ACTUATED ELECTRICAL SWITCH MECHANISM.

1,398,916.

Specification of Letters Patent. Patented Nov. 29, 1921.

Application filed June 27, 1919. Serial No. 307,201.

To all whom it may concern:

Be it known that I, MILLARD F. ROEBLING, a citizen of the United States, residing at Cincinnati, in the county of Hamilton and State of Ohio, have invented certain new and useful Improvements in Time-Actuated Electrical Switch Mechanism, of which the following is a specification.

My invention relates to improvements in on and off time actuated electrical switch mechanism. One of its objects is to provide simple, inexpensive and reliable electrical switch mechanism adapted to be closed at any predetermined period of time and opened at any predetermined later period of time. Another object is to provide such switch mechanism adapted to be employed independently to either open or close the circuit at any predetermined period of time. Another object is to avoid liability of arc formation and injury to the mechanism from such cause, and without undue increase in the cost of the apparatus. Another object is to provide for automatically resetting the switch mechanism to render its entire cycle of movement automatic and clock controlled. My invention also comprises certain details of form, combination, and arrangement, all of which will be fully set forth in the description of the accompanying drawings, in which:

Figure 1 is a front elevation of a mechanism embodying my invention.

Fig. 2 is a plan of the mechanism of Fig. 1 with the dial and pointers detached.

Fig. 3 is a sectional detail of one of the time releasing members.

Fig. 4 is a view similar to Fig. 2 illustrating a modification thereof.

Figs. 5, 6, and 7 are diagrams illustrating successive steps in the operation of closing and opening the electrical circuit.

Fig. 8 is a view similar to Fig. 4 illustrating mechanism in which the circuit is closed by hand the clock is relied upon to open the circuit automatically at a predetermined time period.

Fig. 9 is a view similar to Fig. 8 illustrating mechanism in which the circuit is opened by hand, and the clock is relied upon to close the circuit automatically at a predetermined time period.

The accompanying drawings illustrate the preferred embodiment of my invention, in Figs. 1, 2, and 3 of which A represents a clock casing, which may be of metal, but is

preferably of vulcanized fiber or other non-combustible electrical insulating material. Within the casing A is a frame B comprising two parallel plates of metal secured together by means of a series of spacing rods 14. A clock mechanism of usual construction, of which only the spindle 15 which carries the minute hand 16, and the sleeve 17 which carries the hour hand 18 are illustrated. A pinion 19 on the spindle 15 drives a gear 20 on a stud shaft 21, and a pinion on the stud shaft 21 engages and drives a gear 22 on the sleeve 17 to drive the hour hand at the desired ratio of speed relative to the minute hand. Setting spindles 24 and 25 are respectively journaled to the frame B so as to be rotatably adjustable relative thereto with an appreciable amount of frictional resistance, so that said spindles may be manually adjusted by means of the keys 26 detachably connected thereto at the rear of the frame B and projecting from the rear of the casing A, so that said spindles will remain in any position to which said spindles may be adjusted by said keys. Cam engaging heads 28 and 29 are rigidly mounted upon the respective spindles 24 and 25. Pointers 30 and 31 are also detachably mounted upon said spindles to indicate upon the dials 32 and 33 the position of the tongues 34 of the respective heads 28 and 29 or the time at which the on or off movement of the electrical switch will occur.

Cam members 35 and 36 are loosely mounted upon the spindles 24 and 25 and provided with annular cam faces 37 at one end to engage the tongues 34 of the heads 28 and 29 respectively. Leaf springs 38 and 39 attached by screws to the frame B serve by resiliently engaging the opposite ends of the tubular cam members 35 and 36 to hold their cam faces 37 yieldingly in contact with the tongue 34. The cam members 35 and 36 are provided with gears 40 and 41 which mesh with the pinion 21' and serve to rotate the cams 35 and 36 upon the spindles 24 and 25 once in twelve hours as illustrated, or if desired, once in twenty four hours, depending upon the diameter of the gears 40 and 41 relative to their driving pinion.

When the notches of the cam faces 37 come opposite the tongues 34, the respective cam members 35 and 36 and their gears 40 or 41 move endwise on the spindles 24 and 25, the free ends 42 of the springs 38 and 39 moving with said cam members away from

the frame B. Subsequently the inclined faces of the cam members engage the tongues 34 and thereby restore the cam members 35 and 36 and the free ends 42 of the springs 38 and 39 to their original position.

Rotatably mounted in the frame B are rock shafts 43 and 44 which are respectively provided with rotatably mounted releasing arms or members 45 and 46 adapted to engage the free ends of the springs 38 and 39 when said springs are under maximum tension, and to be released therefrom when said springs 38 and 39 move outwardly from the frame B with the cam members 35 and 36. A spring 47 is attached at opposite ends to arms 48 projecting respectively from the rock shafts 43 and 44, and tends normally to hold said rock shafts in predetermined positions. The rock shafts 43 and 44 are also provided with switch arms 50 and 51. As illustrated in Fig. 2 in full lines the electrical circuit 52 is open at the contacts 50 and 53, and is closed at the contacts 51 and 54, and this would ordinarily be the initial position of the switch mechanism, as for instance where it was desired to turn on the lights 55 in a show window for an hour or so in the evening without making a separate trip to the store for that purpose. Assuming that the spindle 24 is set so that its tongue 34 will enter the notch of its cam face at seven o'clock in the evening, this will cause the spring 38 to move outwardly from the frame B thereby disengaging its free end from the releasing member 45 allowing the shaft 43 to rock, and the switch arm 50 to move from its full line position to its dotted line position where the circuit 52 is closed through the contacts 50 and 53, and the show window is illuminated. Assuming that the spindle 25 is set so that its tongue 34 enters the notch of its cam face at eleven o'clock this will result in the cam 36 and spring 39 moving endwise on the spindle 25 thereby releasing the free end of spring 39 from the arm 46 causing the rock shaft 44 to rock, and the switch arm 51 to move from its full line position to its dotted line position thereby breaking the electrical circuit at the contacts 51 and 54 with a sufficient air gap to insure that any arc initially formed will be broken, thereby cutting off the light from the show window. The electrical circuit 52 may be employed for any other desired purpose. After the cam member 36 and spring 39 have been restored by the inclined cam face to their original position, a push rod 56 mounted on the casing A held in elevated position by means of a spring 57 is forced downwardly by hand, thereby causing its fingers or forked ends 58 inside the casing A to engage and depress the switch arms 50 and 51 from their dotted line positions to their full line positions and at the same time causing the rock shafts to

rock and the arms 45 and 46 to swing so as to reengage the free ends 42 of the spring members 38 and 39 thereby locking the switch arms 50 and 51 in their full line position until they are again released by the clock mechanism. When the switch mechanism is not required for use, it is only necessary to omit to depress the push rod 56 whereupon the circuit will remain open at the contacts 51 and 54.

In the modification Figs. 4 to 7, the mechanism is the same as heretofore described except that a rock shaft 60 corresponding to the rock shafts 43 and 44 is centrally divided and insulated and incased in a jacket 61 of insulating material which jacket is journaled relative to the frame B in brackets 62 and 63. A stop member 64 corresponding to the stop member 45 is insulated from the frame B and from the terminal 65 of the circuit 66, and its free end rests initially upon the free end 67 of the spring arm 38' thereby holding the arm 68 out of contact with the free end of the spring arm 39'. The first step is to release the free end of spring 38' from the end of arm 64, whereupon the rock shaft 61 rocks one step causing the free end of the arm 68 which is in electrical contact with the terminal 65 to contact with the free end of spring arm 39' thereby completing the circuit 69 through the frame B and terminal 69. The next step results in the movement of the spring arm 39' to disengage the end thereof from the end of the arm 68, whereupon the rock shaft 61 rocks another step and comes to rest in the position Fig. 7 with the circuit open. The initial step is represented in Fig. 5 and the second step, in which the circuit is closed is represented in Figs. 4 and 6. The knurled head 70 enables the rock shaft 61 to be manually rocked to reset the mechanism for another cycle of operation.

In Fig. 1 I have illustrated a contact 75 carried by the hour hand 18, which is adapted to make contact with an insulated terminal 77 in the branch circuit 78 for a short period of time once at each revolution of the hour hand, or preferably once in twenty four hours. The branch circuit is opened or closed by hand at the hand switch 79. In the circuit 78 is an electro-magnet 80, which is energized by closing of the circuit 78 so that its armature 76 moves and automatically resets the electrical switch mechanism by depressing the member 56 of Fig. 1, or by 120 rotatably rocking the member 61 of Fig. 5 in opposition to the spring 47' to thereby return the members 64 and 68 from the position Fig. 7 to the position Fig. 5, ready for another cycle of movement. Where such 125 automatic resetting mechanism is employed, the hour hand is preferably arranged to make one revolution in twenty four hours, or other provision is made to avoid closing the circuit 78 more than once in twenty four 130

hours, although such is not absolutely necessary.

In the modification Fig. 8 it is designed that the rock shaft 61' will be actuated by hand and set to substantially the position illustrated in Figs. 6 and 8 in which position the circuit is closed. Then after a predetermined period of time has elapsed, the member 39" will be disengaged by the clock mechanism from the member 68', substantially as heretofore described, and the circuit will thereby be opened and remain open until again closed by hand.

In the modification Fig. 9, it is designed that the rock-shaft 61" will be actuated by hand and set to substantially the position shown in Figs. 5 and 9 with the circuit open, and after a pre-determined period of time the clock will release the member 64' from the member 82, corresponding to the member 38' of Fig. 5, and thereby allow member 83, corresponding to 39" of Figs. 4 and 6, to make electrical contact with member 84, corresponding with member 68 of Fig. 4, to automatically close the circuit.

The apparatus herein illustrated and described is capable of considerable modification without departing from the principle of my invention.

30. What I claim is:

1. A time controlled switch comprising a rotatably mounted releasing member, an electrical switch arm actuated by said rotatably mounted releasing member to open or close an electrical circuit, a clock mechanism, a resiliently actuated cam member driven rotatably by said clock mechanism to release said rotatably mounted releasing member, and a setting spindle having a cam engaging and restraining head, said spindle being rotatably adjustable to predetermine the period of release of said cam and rotatably mounted releasing member.

2. A time controlled switch comprising a rotatably mounted releasing member, an electrical switch arm actuated by said rotatably mounted releasing member to open and close an electrical circuit, a clock mechanism, a resiliently actuated cam member driven rotatably by said clock mechanism to release said rotatably mounted releasing member, a setting spindle having a cam engaging and restraining head, said spindle being rotatably adjustable to predetermine the period of release of said cam and rotatably mounted releasing member, and means to manually rotate said rotatably mounted releasing member to reengage said rotatably mounted releasing member with said cam member.

3. A time controlled switch comprising a plurality of rotatable mounted releasing members to respectively initiate the closing and opening of an electrical circuit, an elec-

trical circuit, means actuated by said rotatably mounted releasing members to close said electrical circuit and to subsequently open said electrical circuit at predetermined periods, a clock mechanism, a plurality of resiliently actuated cam members driven rotatably by said clock mechanism to respectively release said rotatably mounted releasing members, and a plurality of setting spindles each provided with a cam restraining head to engage one of said cams, said spindles being independently rotatably adjustable to predetermine the period of release of said respective cam members.

4. A time controlled switch comprising a plurality of rotatably mounted releasing members to respectively initiate the closing and opening of an electrical circuit, an electrical circuit, means actuated by said rotatably mounted releasing members to close said electrical circuit and to subsequently open said electrical circuit at predetermined periods, a clock mechanism, a plurality of resiliently actuated cam members driven rotatably by said clock mechanism to respectively release said rotatably mounted releasing members, a plurality of setting spindles each provided with a cam restraining head to engage one of said cams, said spindles being independently rotatably adjustable to predetermine the period of release of said respective cam members, and means to manually rotate said rotatably mounted releasing members to reengage said rotatably mounted releasing members with said cam members.

5. A time controlled switch comprising a rotatably mounted releasing member, an electrical switch arm actuated by said rotatably mounted releasing member to open and close an electrical circuit, a clock mechanism, a resiliently actuated cam member driven rotatably by said clock mechanism to release said rotatably mounted releasing member, a setting spindle having a cam engaging and restraining head, said spindle being rotatably adjustable to predetermine the period of release of said cam and rotatably mounted releasing member, and means automatically controlled by said clock mechanism to rotate said rotatably mounted releasing member to reengage said rotatably mounted releasing member with said cam member.

6. A time controlled switch comprising an electrical switch, a clock mechanism, means actuated at predetermined periods of time by said clock to successively close and open said circuit, and means periodically actuated by said clock mechanism to reset said actuating means in position to again successively close and open said circuit.

In testimony whereof I have affixed my signature.

MILLARD F. ROEBLING.
